INTERNAL-COMBUSTION ENGINE

Carman C. Tate, Mexico City, Mexico, assignor to
Phillips Petroleum Company, a corporation of
Delaware

Application November 13, 1945, Serial No. 628,308

11 Claims. (Cl. 123—119)

1

This invention relates to internal combustion engines. In one aspect this invention relates to a method and apparatus for the injection of fuel mixtures into the combustion chamber of an internal combustion engine. In another aspect this invention relates to a new type of internal combustion engine.

Most conventional internal combustion engines depend upon suction or upon some mechanically operated injection means for supplying the fuel to the combustion chamber of the engine. In some internal combustion engines where the fuel is supplied to the combustion chamber by suction created by the movement of the piston within the cylinder of the engine, both fuel and air surge into the combustion chamber and are ignited. In other types of engines, such as the Diesel engine, air is introduced or drawn into the combustion chamber and compressed therein, and then the fuel is injected into the chamber under pressure by some mechanical means. In those types of injection systems where either compression or suction is used to introduce the fuel mixture into the engine, the fuel supply mechanism is relatively complicated. Also, the introduction of the fuel into the combustion chamber of the engine can only be made at a particular time in the combustion cycle of the engine since the introduction of either the fuel or the air depends upon the movement of the piston within the engine cylinder. Such limitations reduce the capacity and efficiency of the engine.

In the case of the ordinary carburetor used for mixing the fuel and air, which depends upon the suction of air into the combustion chamber by the downward stroke of the piston, too much fuel is brought into the chamber when the engine is operating at full capacity and too little fuel is brought into the chamber when the engine is operating at low capacity unless some accessory compensating means is provided. It is, therefore, much to be desired to provide a method and apparatus to inject a constant ratio of fuel and air into the combustion chamber regardless of the operating conditions of the engine and which does not depend upon accessory compensating devices to maintain a constant ratio of fuel and air. It is also well known that the various types of internal combustion engines are limited to certain fuels because of their construction and the character of the combustion mixture. It is therefore desirable to obtain an engine which can use a broad range of fuels without materially changing the fundamental characteristics of the engine itself by assuring complete vaporization and

2

intimate mixing of fuel and air, either in the combustion chamber or prior to introduction into the combustion chamber.

It is an object of this invention to provide a new type of internal combustion engine capable of using a broader range of fuels and having a means for injecting fuel and air into the combustion chamber against atmospheric or higher pressures.

5 10 It is also an object of this invention to increase the accuracy in maintaining fuel and air ratios in the injection of fuel into an internal combustion engine.

15 It is another object of this invention to obtain substantially complete vaporization of fuel prior to injection into the combustion chamber of an internal combustion engine.

20 Still another object is to remove the necessity of using conventional carburetors and obtaining better performance with lower octane fuels by a simple form of injection of fuel into an internal combustion engine.

25 It is also an object to separately introduce fuel and air into a combustion chamber of an internal combustion engine.

30 It is still a further object to increase the combustion properties of various fuels by the new and novel arrangement for injection of fuel into a combustion chamber of an internal combustion engine.

35 Other objects of the invention are to accomplish these objects with a few moving parts, doing so over a wide range, and obtain optimum operation of internal combustion engines without detonation of the fuel during combustion.

Numerous other objects and advantages will be obvious to those skilled in the art from the accompanying specification, claims and drawings.

40 In the drawings:
Figure 1 is an elevational view with parts broken away diagrammatically illustrating one embodiment of the present invention to the injection of fuel into the combustion chamber of an internal combustion engine.

45 Figures 2 and 3 are elevational views with parts broken away showing diagrammatically a modified method and means similar to Figure 1 for the injection of fuel into the combustion chamber of an internal combustion engine. In Figure 2 fuel and air are injected together into the internal combustion engine while in Figure 3 fuel is introduced separately from the air.

50 In Figure 1 a fuel tank 4 is provided for the storage and supply of fuel for operating an internal combustion engine 28. A tank 8 is pro-

vided as a means for holding a constant level of liquid fuel and is connected by an open conduit 11 to a tank 9 which contains gases under super-atmospheric pressure. Float 12, with transmission means 13, maintains a constant level in tank 8 by operating pump 6 which pumps fuel from fuel tank 4 through conduit 7. An injection means 17 is used to admix fuel and air and inject the resulting mixture into a surge tank 24. Needle valve 16 and valve 19, attached to a throttle 23 by transmission means 22, regulate the flow of fuel and gases from tanks 8 and 9. Numeral 21 indicates the flow of air into injection means 17.

Element 28 represents an internal combustion engine complete with a cylindrical piston 29, a connecting rod 31, a crank arm 32, a crankshaft 33, a fuel inlet valve 36, and gas outlet valves 38 and 41. Element 27 is a cylindrical combustion chamber within said internal combustion engine 28. Valve 36, operated by a cam 37, admits fuel and air into combustion chamber 27 of engine 28 through line 26. Valve 38, operated by a cam 39, permits the flow of a portion of the combustion product gases from chamber 27 into line 43 and thence to tank 9. Valve 41, operated by a cam 42, allows the escape of exhaust gases from chamber 27 into line 47. Element 44 is a conventional pressure control valve which is controlled by the pressure maintained on tank 9 by transmission means 46. A spark plug 34 connected to a battery or magneto (not shown) provides the necessary ignition means for a fuel and air mixture in chamber 27 of engine 28.

Combustion engine 28 may comprise a series of cylinders or combustion chambers containing pistons and valves in each cylinder, and in such a case surge chamber 24 and conduit 26 are combined to form a manifold for the passage of a fuel mixture simultaneously to all cylinders of the engine.

The internal combustion engine itself may be constructed of cast iron, steel or appropriate alloys where wear and corrosion require. The tanks 8 and 9 and the accessory equipment can also be constructed of cast iron or steel and may be lined with corrosion resistant alloys if necessary.

Figure 2 is similar to Figure 1 and consequently the description of the elements of Figure 2 will be brief. A tank 54 is provided for the storage of fuel and gases from an internal combustion engine 68. Element 61 is an injection means for the injection of fuel and air into cylindrical combustion chamber 68 of an internal combustion engine 68. Valves 57 and 59, with a transmission means 63 connected to a throttle 64, regulate the flow of fuel and gases through conduits 56 and 58, respectively. Internal combustion engine 68 is complete and includes cylindrical piston 71, arms 72 and 73 and crankshaft 74. Element 79 is a spark plug or other similar means connected to a battery or magneto (not shown) for igniting a fuel and air mixture in chamber 68.

Element 61 is a valve for admission of fuel and air into a combustion chamber 68. A valve 81 is provided for the release of combustion product gases from the combustion chamber 68, and valve 83 permits the escape of exhaust gases from combustion chamber 68. Element 88 is a conventional pressure control valve with a transmission means 89 controlled by the pressure in tank 54. A conduit 91 is a means for admitting fuel to tank 54, when necessary.

Injection means 17 and 61 of both Figures

1 and 2 comprises a nozzle 15 and 60, respectively, in a hollow casing or cylinder through which gases expand. The hollow casing or cylinder of the injection means has a restricted area or throat 20 and 65, respectively, into which the gases expand and this throat is open to the atmosphere at one end and to a conduit or container at the other end. The throat or restricted area has an inlet therein for the admission of fuel into the gaseous stream flowing therethrough. Preferably, the fuel inlet is located in the throat of the injection means but the fuel inlet may be located in any position so long as the fuel is introduced into a gaseous stream. Obviously, many other types or construction of an injection means may be used without departing from the scope of the invention.

Figure 3 represents a preferred embodiment of the present invention and is similar to Figures 1 and 2 with certain modifications as will become apparent from the description of the apparatus and operation of the combustion process. Briefly, a tank 101 is provided for the storage of fuel and gases from an internal combustion engine 124. Valves 104 and 106 regulate the flow of fuel and gases through conduits 103 and 102, respectively. Element 110 represents a vaporizer or preheater for fuel and gases from tank 101 and in other respects resembles surge tank 24 of Figure 1. Vaporizer 110 has an inner chamber containing baffles 113 surrounded by an outer jacket or shell 111. Exhaust gases from combustion engine 124 flow into jacket 111 of vaporizer 110 through conduit 135 and are passed therefrom to fuel tank 101 through conduit 147.

Internal combustion engine 124 is complete and includes moveable piston 126, arms 128 and 129 and crankshaft 130. Element 132 is a spark plug or other similar means connected to a battery or magneto (not shown) for igniting a combustible fuel and air mixture in a combustion chamber 125 of internal combustion engine 124. Element 116 is a valve for admission of fuel into combustion chamber 125. Element 119 is a similar valve for the admission of air into combustion chamber 125. A valve 133 is provided for the release of combustion product gases from the combustion chamber 125 into conduit 135 and thence to fuel tank 101. Element 140 is a conventional pressure control valve with a transmission means 145 for controlling the pressure in tank 101. A conduit 148 is provided for admitting fuel to tank 101 when necessary. A valve 136 is provided for exhausting combustion product gases from combustion chamber 125 at the appropriate time in the combustion cycle. Other elements of Figure 3, such as throttle 109 connected to flow control valve 107 by transmission means 108, cams 118, 137, 121, 134, and various conduits, are similar to the corresponding elements of Figures 1 and 2; consequently, further discussion of these elements is deemed unnecessary.

It is noted that in the construction of Figure 3 that the injection of the air and fuel into combustion chamber 125 is separate, and that the throttle is connected to a flow control valve 107 after admixing the gases and fuel from tank 101 and not before as in Figures 1 and 2.

Operation

In Figure 1 liquid fuel from storage tank 4 passes to tank 8 by means of pump 6 and conduit 7. The fuel may comprise gasoline, kerosene, fuel oil or any type of fluid fuel capable of combustion

in engine 28. Float 12 controls pump 6 through transmission means 13 so that the liquid fuel level in tank 8 is maintained constant therein. Gases under superatmospheric pressure are in the space above the liquid level in tank 8. These gases come from tank 9 to tank 8 by open conduit 11.

Combustion product gases, which are conveyed from engine 28, are confined in tank 9 and are held under a relatively high superatmospheric pressure and at a relatively high superatmospheric temperature therein. The pressure in tanks 8 and 9 may be about 100 to about 600 pounds per square inch gage, and the temperature of the gases may be about 300 to about 1000° F. or more. It is preferable to use superatmospheric temperatures and pressures within the ranges indicated, but lower or higher temperatures and pressures may be employed without departing from the scope of the invention. A reducing valve (not shown) may be included in line 11 to reduce the pressure of the gases flowing from tank 9 to tank 8, if desired. Tank 9 may also have a condensate outlet (not shown) in the bottom thereof to remove any condensed water which may collect therein.

Liquid fuel flows from tank 8 through line 14 and needle valve 16 into injection means 17 by means of the pressure exerted by the gases present above the liquid level in tank 8; simultaneously gases under superatmospheric pressures flow from tank 9 through line 18 and valve 19 to expand through nozzle 15 of injection means 17. Other means may be used to aid in forcing fuel from tank 8 into injection means 17 as well as by the pressure exerted by the gases in tank 8, such as by gravity or an auxiliary fuel pump, a conventional carburetor, etc. As the result of the increase in velocity of the gases caused by their expansion through nozzle 15 into the reduced area of the throat 20 of injection means 17, air is drawn in from the open end of injection means 17, as indicated by numeral 21, and admixed with the gases from tank 9. The admixture of air and gases, which is at a superatmospheric temperature, contacts the liquid fuel flowing into the gas stream adjacent to throat 20 of injection means 17 through line 14 and either vaporizes or forms a fine spray or mist of the fuel. The resulting turbulent admixture of air, gases and fuel, by its own inertia and the pressure of the expanding gases, passes into surge tank 24. The turbulent flow of air and fuel through injection means 17 assures uniform mixing of the air and fuel prior to introduction into combustion chamber 27.

The fuel from tank 8 may be atomized when it is passed into injection means 17 by using a nozzle or atomizer or the like (not shown) on line 14. The pressure of the gases in tank 8 forces the fuel through line 14 and needle valve 16 and any nozzle or atomizer attached to line 14.

The gaseous mixture in tank 24 is at a superatmospheric pressure but somewhat less than the pressure of gases in tank 9 or tank 8.

Throttle 23 regulates the quantity of fuel and gases flowing through lines 14 and 18, and in this way regulates the amount of the fuel mixture and the pressure in surge tank 24. Throttle 23 operates valves 16 and 19 by transmission means 22. Valves 16 and 19 are adjusted so that the appropriate ratio of fuel and air necessary to make a combustible mixture are admixed in injection means 17.

Engine 28 is an internal combustion engine having a reciprocating piston 29 which rotates crankshaft 33 by means of arms 31 and 32. 75

When the piston 29 is at the top of its upward stroke the space between the upper surface of the piston and the top of the cylinder constitutes a combustion zone designated as 27. When the piston 29 is at or near this position valve 36 is opened by cam 37 to allow the fuel and air mixture from surge tank 24 to enter chamber 27 by virtue of the pressure of the fuel mixture in surge tank 24. Cam 37 is operated from crankshaft 33 by a set of gears or chains in the conventional manner familiar in the operation of internal combustion engines. When valve 36 is open the fuel mixture, which is under superatmospheric pressure in surge tank 24, passes through line 26 into combustion chamber 27. When piston 29 is in position for its downward stroke valve 36 is closed and the fuel mixture is ignited by spark plug 34 or other means. During the opening of valve 36 and during the downward stroke of piston 29 valves 41 and 38 remain closed. Upon ignition of the fuel mixture in chamber 27 the resulting gaseous mixture attains a high superatmospheric temperature and pressure and forces piston 29 downward rotating crankshaft 33 to expand the gases and do work. Thereabouts or shortly after piston 29 begins its downward stroke, the combustion of the fuel mixture is substantially completed and the pressure attained by the gaseous mixture as the result of the combustion in chamber 27 will be approximately at its maximum being between about 300 and about 600 pounds per square inch gage, depending upon the type of internal combustion engine being operated. Preferably, when the pressure of the gaseous mixture approaches the maximum in chamber 27 valve 38 is opened by cam 39 allowing part of the product gases to flow through line 43 and valve 44 into tank 9 and thence to tank 8. However, gases may be passed to tank 9 at any time during the downward stroke of piston 29, if desired. When piston 29 has started its downward stroke, and after a portion of the combustion product gases have passed through line 43 to tank 9, valve 38 is closed. Upon completion of the downward stroke of piston 29 valve 41 is opened by cam 43 so that the remaining gases can pass out of the cylinder or chamber 27 through line 47. This valve 41 remains open until the piston 29 has attained its former position at the top of its stroke, and then the previously discussed cycle is repeated.

Pressure control valve 44 by transmission means 46 regulates the pressure in tank 9 so that if the pressure in tank 9 exceeds a predetermined amount, valve 44 is closed and the gases which normally would pass through line 43 to tank 9 are expanded against piston 29.

It is within the scope of the present invention to locate gas outlet valve 38 in other positions than at the top of cylinder or combustion chamber 27 as shown. In this respect gas outlet valve 38 may be positioned at the lower end of combustion chamber 27 so that it is opened by the movement of the piston below the outlet valve itself. Thus, gases under pressure would be passed to tank 9 after the downward stroke of piston 29 rather than preceding the downward stroke. In some instances exhaust gas outlet valve 41, cam 42, and conduit 47 may be omitted entirely, and instead of the exhaust gases escaping through conduit 47, these gases would flow through gas valve 38 and conduit 43 directly to gas tank 9. A portion of the gases may be vented (not shown) to the air from tank 9.

if necessary, or directly vented (not shown) from conduit 43. If gases are passed to tank 9 after the downward stroke of piston 29, either through valve 38 as indicated or through a valve located elsewhere, the downward stroke of piston 29 is completed and the gas outlet valve is opened while a substantial superatmospheric pressure is still exerted by the expanding gases in chamber 27.

The above described combustion cycle is only one of many types which can be used in the present invention and, as will be noted, it is similar to a two-cycle combustion process. The present invention may be applied to a four-cycle combustion process where the fuel is injected in the first cycle, compressed in the second cycle, combusted in the third cycle and exhausted in the fourth cycle. Air may also be drawn into chamber 27 from another inlet (not shown) and compressed in chamber 27 prior to the injection of the fuel or fuel-air mixture therein. It will be apparent to those skilled in the art that the present invention is equally applicable to both Diesel and Otto-type internal combustion engines and the various modifications of the same. In case of the Diesel engine, spark plug 34 may be omitted since ignition of the fuel mixture will depend on the temperature and pressure in the engine cylinder or combustion chamber 27.

Figure 2 is a modified method and apparatus of the embodiment of Figure 1 and for this reason the operation of Figure 2 will be discussed only briefly. Fuel passes from tank 54 through line 56 and needle valve 57 to injection means 61. The fuel may be sprayed or atomized into the gas stream adjacent to throat 65 of injection means 61 by a nozzle or atomizer (not shown) on line 56 as described in the operation of Figure 1. Combustion product gases pass from fuel tank 54 to nozzle 60 and injection means 61 by means of line 58 and valve 59. It should be noted that fuel tank 54 serves for both the storage of fuel and a container for the combustion product gases as well, thus eliminating the gas tank 9 of Figure 1.

Gases passing through restricted area 65 of injection means 61 draw in air as indicated by numeral 62 and cause a turbulent mixture of air, gases and fuel in injection means 61. Since the gases are at a relatively high temperature the liquid fuel is preheated in tank 54 and as it enters the gas stream in injection means 61, if the temperature is high enough, the fuel may be vaporized. In a similar manner as in Figure 1, when the piston 71 of engine 69 is at the top of its stroke valve 67 is opened by cam 76 and lever arm 77 so that the fuel-air mixture from injection means 61 passes into combustion zone 68 through conduit 66. Needle valve 57 and valve 59 are connected to valve 67 by transmission means 78 so that when valve 67 is open valves 57 and 59 are also open and when valve 67 is closed valves 57 and 59 are also closed. The amount of fuel flowing through line 56 and the amount of gases flowing through line 58 are regulated by means of throttle 64 and connecting means 63. In this manner when valve 67 is open the amount of a combustible mixture of fuel and air injected into combustion chamber 68 can be controlled by throttle 64.

Valve 67 is closed and the fuel-air mixture is ignited by spark plug 79 or like means. At approximately the completion of the combustion of the fuel mixture the pressure in combustion

chamber 68 approaches a maximum, and valve 81 is then opened by means of cam 82. Gases at a relatively high superatmospheric pressure pass out of combustion chamber 68 through line 86 and valve 88 into fuel tank 54. Gases expanding in chamber 68 force piston 71 downward through the cylinder of engine 69 rotating crankshaft 74 by means of arms 72 and 73, during which time valve 67 remains closed. As piston 71 proceeds on its downward stroke, valve 81 is closed and remaining gases exert their pressure against piston 71. On the upward stroke of piston 71 valve 83 is opened by means of cam 84 so that the expanded gases in chamber 68 are exhausted through line 87.

Pressure control valve 88, by connecting means 89, controls the pressure in fuel tank 54. Line 91 is available for the admission of fuel into tank 54, when necessary.

The fuel-air mixture in the embodiment of Figure 2 is injected directly into combustion chamber 68 eliminating the surge tank 24 of Figure 1.

As previously indicated, Figure 3 is a preferred embodiment of the present invention. Since the operation of Figure 3 is similar to the operation of Figures 1 and 2, it will be discussed only briefly with the various modifications pointed out in particular. Fuel passes from tank 101 through conduit 103 and needle valve 104 or like means to conduit 102. Gases from fuel tank 101 pass therefrom to conduit 102 and valve 106 or like means to vaporizer 110. Conduit 103 is inserted in or connected to conduit 102 in such manner that fuel from tank 101 flows into conduit 102. The quantity of fuel and gases which admix at the juncture of conduits 103 and 102 is regulated partially by setting valves 104 and 106 and partially by the aspiration effect of gases flowing through conduit 102 past the juncture of conduit 103 therewith. The fuel may be sprayed or atomized into the gas stream of conduit 102 by a nozzle or atomizer (not shown) attached to conduit 103 at the juncture of the conduits 102 and 103. The intimate mixture of gases and fuel, either partially or wholly vapor, usually in a fine spray, is passed to vaporizer 110. In vaporizer 110 the mixture of fuel and gas is heated and any liquid fuel is vaporized. Baffles 113 direct the flow of the mixture through vaporizer 110 for sufficient time to assure heating of the mixture. Some liquid still may remain with the gases in the form of a spray, but in most cases the liquid fuel will be entirely vaporized. The mixture from vaporizer 110 passes therefrom through line 114 and valve 116 into combustion chamber 125. Valve 116 is operated as previously discussed in Figures 1 and 2 by cam 118. Air in the appropriate quantity is passed into combustion chamber 125 through valve 119 which is operated by cam 120. It is to be noted that the air and the fuel is injected into combustion chamber 125 separately and that the fuel mixture is preheated in vaporizer 110.

When piston 126 of combustion engine 124 is at the bottom of its downward stroke, valve 116 is opened by cam 118 so that the fuel mixture from vaporizer 110 passes into combustion chamber 125 through conduit 114. The amount of fuel injected is regulated by control valve 107 which is connected to throttle 109 by transmission means 108. Air through valve 119 is admitted to the chamber 125 previous to the admission of fuel through valve 116, i. e., drawn in by the downstroke of piston 126. The amount of air admitted to chamber 125 is regulated by a damper or other means not shown on an air intake conduit 123. Piston 126 starts on its upward stroke and all the

valves are generally closed leading to or from combustion chamber 125; however, in some instances valve 116 may remain open during the upward stroke and fuel is continuously introduced. When piston 126 has reached substantially the top of its upward stroke the combustible mixture of air, fuel and gases in combustion chamber 125 are ignited by spark plug 132 or like means. As previously discussed, when maximum pressure is reached in chamber 125, valve 133 is open and a portion of the gases in combustion chamber 125 pass into conduit 135. Valve 133 is operated by cam 134 in a similar manner as the corresponding valves 36 and 81 of Figures 1 and 2, respectively. These combustion product gases pass through conduit 135 through the outer jacket 111 of vaporizer 110. From vaporizer 110 the gases pass through conduit 147 to fuel tank 101. Pressure is maintained in fuel tank 101 by pressure control valve 140 and transmission means 145 as previously discussed in connection with valves 44 and 88 of Figures 1 and 2, respectively.

After a portion of the gases from combustion chamber 125 have passed therefrom, valve 133 is closed and the remaining pressure of gases in chamber 125 is exerted against piston 126 forcing it downward to rotate crankshaft 130 by means of rods 128 and 129. At the lower end of the downward stroke of piston 126 valve 136 is opened at the appropriate time by cam 137 and remains open during the subsequent upward stroke of piston 126 which forces exhaust gases from combustion chamber 125 through conduit 138. After piston 126 has again reached the top of its upward stroke valve 136 is closed by cam 137 and air inlet valve 119 is opened. On the downward stroke of piston 126 air is drawn into combustion chamber 125 through valve 119 which remains open and is operated by cam 121. After the piston is at the bottom of its downward stroke, having drawn air into combustion chamber 125, valve 119 is closed and the four-cycle combustion process previously described is repeated.

In the embodiment of Figure 2, in case the fuel in tank 54 is a finely divided solid, such as charcoal, it will be forced through line 56 into injection means 61 and will be blown into chamber 68.

Instead of valve 38 and cam 39 of Figure 1 and valve 81 and cam 82 of Figure 2, and valve 133 and cam 134 of Figure 3, conventional check valves allowing the flow of gases only in the direction of tank 9 or 54 or 101 may be substituted in the place of the valves shown. Valve 44 of Figure 1 and valve 88 of Figure 2 and valve 140 of Figure 3 may also be omitted and in such case the check valve substituted for the valves shown in Figures 1, 2 and 3 may have a pressure release control thereon, such as a spring loaded check valve, to allow the gases to pass from the combustion chamber when the gases therein reach a certain pressure. Such a check valve prevents the flow of the gases from the storage tank back to the combustion chamber when the pressure therein is low.

By the use of valves in the fuel line and exhaust gas line leading to the injection means of Figures 1 and 2, the ratio of fuel to air may be accurately controlled at all capacities of the engine which is a distinct advantage over the normal method of mixing fuel and air by carburetors. Also, since the gases from the engine are passed to the gas tank when the pressure in the combustion chamber is highest, the tendency for detonation or knocking of the fuel is

minimized. The temperature of the combustion product gases is relatively high and consequently this heat may be utilized to preheat both the fuel and the air or fuel alone as in Figure 3 prior to its introduction into the combustion chamber of the internal combustion engine resulting in an increase in the efficiency of the engine. This preheating the fuel aids in the vaporization of many fuels which could not normally be vaporized by those methods of carburetion used in the prior art. Furthermore, since the exhaust gases contain water as a by-product of combustion, the fuel-air mixture resulting from the application of this invention will contain some water. This water in the fuel-air mixture is a distinct advantage as is well known in the art since it improves the progressive burning characteristics of the fuel in the combustion chamber of an internal combustion engine. Another advantage to the present injection method is that the injection may be made against relatively high pressures permitting the injection to be made over a broad range of time during the combustion cycle and under conditions of super-atmospheric pressure in the combustion chamber. Thus, injection of fuel or fuel and air may be made even during the compression stroke of the combustion cycle. The process of injection is also conveniently carried out without the use of various moving parts as is common in most injection systems, especially in the case of the embodiment of Figure 3.

It is to be noted that the combustion process described with regard to Figures 1 and 2 are two-cycle processes while the process described with regard to Figure 3 is a four-cycle process. Either a two or four-cycle process may be used with the embodiment of the invention represented by any of the figures, and, consequently, the invention is not limited to the particular type of combustion cycle.

Having described preferred forms of the present invention and having pointed out the principal considerations to be observed in construction and operation of equivalent systems, it is obvious that various other changes and applications can be made without departing from the scope of this invention, which is defined only by the following claims.

I claim:

1. An internal combustion engine which comprises in combination a cylindrical combustion chamber having a piston therein capable of reciprocating in said combustion chamber, said piston attached to a crankshaft in such a manner that the reciprocating movement of said piston rotates said crankshaft, an inlet valve positioned in the upper portion of said combustion chamber to admit a combustible mixture into said combustion chamber, two gas outlet valves positioned in the upper portion of said combustion chamber, means for opening and closing said inlet and outlet valves relative to the position of said piston in said combustion chamber, means for igniting a combustible mixture in said combustion chamber, a fuel tank, a gas tank, an open conduit communicating between said fuel tank and said gas tank, a conduit communicating between said gas tank and one of said gas outlet valves, an injection means having a hollow cylindrical casing and a nozzle projecting into a restricted area in said casing of said injection means, said restricted area having a fuel inlet adjacent thereto and an opening to the atmosphere at one end thereof,

a conduit communicating between said gas tank and said nozzle of said injection means having a valve therein for the control of the flow of gas therethrough, a conduit communicating between said fuel tank and said fuel inlet adjacent to said restricted area of said injection means having a valve therein for the control of the flow of fluid therethrough, a surge tank, a conduit communicating between said injection means and said surge tank, and a conduit communicating between said surge tank and said inlet valve of said combustion chamber.

2. An internal combustion engine which comprises in combination a cylindrical combustion chamber having a piston therein capable of reciprocating in said combustion chamber, said piston attached to a crankshaft in such a manner that the reciprocating movement of said piston rotates said crankshaft, an inlet valve positioned in the upper portion of said combustion chamber to admit a combustionable mixture into said combustion chamber, two gas outlet valves positioned in the upper portion of said combustion chamber, means for opening and closing said inlet and outlet valves relative to the position of said piston in said combustion chamber, a fuel tank, a gas tank, an open conduit communicating between said fuel tank and said gas tank, a conduit communicating between said gas tank and one of said gas outlet valves, an injection means having a fuel inlet, a gas inlet, and an opening to the atmosphere, a conduit communicating between said gas tank and said gas inlet of said injection means having a valve therein for the control of the flow of gas therethrough, a conduit communicating between said fuel tank and said fuel inlet of said injection means having a valve therein for the control of the flow of fluid therethrough, a surge tank, a conduit communicating between said injection means and said surge tank, and a conduit communicating between said surge tank and said inlet valve of said combustion chamber.

3. An internal combustion engine which comprises in combination a combustion chamber having a piston therein capable of reciprocating in said combustion chamber, said piston attached to a crankshaft in such a manner that the reciprocating movement of said piston rotates said crankshaft, two inlet valves positioned in the upper portion of said combustion chamber, one inlet valve to admit a fuel mixture into said combustion chamber, the other inlet valve to admit air into said combustion chamber, two gas outlet valves positioned in the upper portion of said combustion chamber, means for opening and closing said inlet valves and outlet valves relative to the position of said piston in said combustion chamber, a fuel tank, a first conduit communicating between said fuel tank and one of said gas outlet valves, a second conduit communicating between the upper portion of said fuel tank and said fuel inlet valve of said combustion chamber having a valve therein for the control of the flow of gas therethrough, a third conduit communicating between the lower portion of said fuel tank and the aforesaid second conduit upstream from said valve in said second conduit forming a juncture therewith, and means for exchanging heat between said first conduit and a portion of said second conduit downstream from said juncture of said third conduit therewith.

4. An internal combustion engine which comprises in combination a combustion chamber having a piston therein capable of reciprocating in said combustion chamber, an inlet valve in said

combustion chamber to admit a fuel mixture into said chamber, two gas outlet valves in said combustion chamber, means for opening and closing said inlet and outlet valves relative to the position of said piston in said combustion chamber, a fuel tank, a conduit communicating between said fuel tank and one of said gas outlet valves, and a branched conduit communicating between said fuel tank and said inlet valve, one branch connected to the upper portion of said fuel tank and the other branch connected to the lower portion of said fuel tank.

5. An internal combustion engine which comprises in combination a cylindrical combustion chamber having a piston therein capable to reciprocating in said combustion chamber, said piston attached to a crankshaft in such a manner that the reciprocating movement of said piston rotates said crankshaft, an inlet valve positioned in the upper portion of said combustion chamber to admit a combustionable mixture into said combustion chamber, two gas outlet valves positioned in the upper portion of said combustion chamber, means for opening and closing said inlet and outlet valves relative to the position of said piston in said combustion chamber, a fuel tank, a conduit communicating between said tank and one of said gas outlet valves, an injection means having a nozzle projecting into a restricted area in said injection means, said restricted area having an opening to the atmosphere, a conduit communicating between the upper portion of said tank and said nozzle of said injection means having a valve therein for the control of the flow of gas therethrough, a conduit communicating between the lower portion of said tank and said injection means having a valve therein for the control of the flow of fluid therethrough, a surge tank, a conduit communicating between said injection means and said surge tank, and a conduit communicating between said surge tank and said inlet valve of said combustion chamber.

6. An internal combustion engine which comprises in combination a combustion chamber having a piston therein capable of reciprocating in said combustion chamber, an inlet valve positioned in the upper portion of said combustion chamber to admit a combustionable mixture into said combustion chamber, two gas outlet valves positioned in the upper portion of said combustion chamber, means for opening and closing said inlet and outlet valves relative to the position of said piston in said combustion chamber, a fuel tank, a conduit communicating between said tank and one of said gas outlet valves, an injection means having a hollow casing, a fuel inlet therein and a nozzle projecting into a restricted area in said casing of said injection means, said restricted area having an opening to the atmosphere, a conduit communicating between said tank and said nozzle of said injection means having a valve therein for the control of the flow of gas therethrough, a conduit communicating between said tank and said fuel inlet of said injection means having a valve therein for the control of the flow of fluid therethrough, and a conduit communicating between said injection means and said inlet valve of said combustion chamber.

7. An internal combustion engine which comprises in combination a combustion chamber having a piston therein capable of reciprocating in said combustion chamber, an inlet valve in said combustion chamber, two gas outlet valves in said combustion chamber, means for opening and closing said inlet and outlet valves relative to the

position of said piston in said combustion chamber, a fuel tank, a conduit communicating between said fuel tank and one of said gas outlet valves, an injection means, a conduit communicating between the upper portion of said fuel tank and said injection means, another conduit communicating between the lower portion of said fuel tank and said injection means, and a conduit communicating between said injection means and said inlet valve of said combustion chamber.

8. In an internal combustion engine comprising in combination a cylindrical combustion chamber having a moveable piston therein which can reciprocate in said combustion chamber, said piston attached to a crankshaft in such a manner that the reciprocating movement of said piston rotates said crankshaft to perform work, a fuel inlet valve and a gas outlet valve positioned in the upper portion of said combustion chamber, means for opening and closing said inlet and outlet valves relative to the position of said piston in said combustion chamber, means for igniting a combustible mixture introduced into said combustion chamber, and a fuel tank, the improvement which comprises a second gas outlet valve in said upper portion of said combustion chamber, means for operating said valve relative to the position of said piston in said combustion chamber, a gas tank, a conduit communicating between said second gas outlet valve and said gas tank, a conduit communicating between the upper portion of said fuel tank and said gas tank, an injection means having a hollow cylindrical casing and a nozzle projecting into a restricted area in said casing of said injection means, said restricted area of said injection means having a fuel inlet adjacent thereto and an opening to the atmosphere at one end thereof, a conduit communicating between said gas tank and said nozzle of said injection means having a valve therein for the control of the flow of gas therethrough, a conduit communicating between the lower portion of said fuel tank and said fuel inlet adjacent to said restricted area of said injection means having a valve therein for the control of the flow of fluid therethrough, and a conduit between said injection means and said fuel inlet valve through which a fuel-air mixture is conveyed to said combustion chamber by the expansion of gases in said injection means.

9. In an internal combustion engine comprising in combination a cylindrical combustion chamber having a moveable piston therein which can reciprocate in said combustion chamber, said piston attached to a crankshaft in such a manner that the reciprocating movement of said piston rotates said crankshaft, a fuel inlet valve and a gas outlet valve positioned in the upper portion of said combustion chamber, means for opening and closing said inlet and outlet valves relative to the position of said piston in said combustion chamber, and a fuel tank, the improvement which comprises a second gas outlet valve in said combustion chamber, a conduit communicating between said second gas outlet valve and said fuel tank, an injection means having a fuel inlet, a gas inlet, and an opening to the atmosphere, a conduit communicating between the upper portion of said fuel tank and said gas inlet of

said injection means, another conduit communicating between the lower portion of said fuel tank and said fuel inlet of said injection means, and a conduit between said injection means and said fuel inlet valve through which a fuel-air mixture is conveyed to said combustion chamber by the expansion of gases in said injection means.

10. In an internal combustion engine comprising in combination a combustion chamber having a moveable piston therein which can reciprocate in said combustion chamber, a fuel inlet valve and a gas outlet valve in said combustion chamber, means for opening and closing said inlet and outlet valves relative to the position of said piston in said combustion chamber, and a fuel tank, the improvement which comprises a gas tank, a conduit communicating between said gas outlet valve and said gas tank for the flow of gases from said combustion chamber thereto, a conduit communicating between said gas tank and said fuel tank, an injection means having a fuel inlet, a gas inlet and an open communication means to the atmosphere therein, a conduit communicating between said fuel tank and said fuel inlet of said injection means, a conduit communicating between said gas tank and said fuel tank and said gas inlet of said injection means, and said injection means attached to said inlet valve of said combustion chamber so that a fuel and air mixture is injected therein by the expansion of gases from said gas tank in said injection means.
11. In an internal combustion engine comprising in combination a combustion chamber having a moveable piston therein which can reciprocate in said combustion chamber, an inlet valve and an outlet valve in said combustion chamber, means for opening and closing said inlet and outlet valves relative to the position of said piston in said combustion chamber, and a fuel tank, the improvement which comprises a first conduit communicating between said outlet valve and said fuel tank for the flow of gases from said combustion chamber thereto, a second conduit communicating between the upper portion of said fuel tank and said inlet valve in said combustion chamber, a third conduit communicating between the lower portion of said fuel tank and said second conduit to form a juncture therewith, and means for controlling the flow of fluid through said second conduit positioned downstream from said juncture between said second and third conduits.
